[57] CLAIM

The ornamental design for a beverage can tray, as shown and described.

DESCRIPTION

FIG. 1 is a top plan view of a beverage can tray showing our new design;

FIG. 2 is a bottom plan view thereof;

FIG. 3 is a side elevational view thereof;

FIG. 4 is a rear elevational view thereof, the opposite side being identical;

FIG. 5 is a sectional view taken along line 5—5 of FIG. 1;

FIG. 6 is a fragmentary bottom plan view of an alternate embodiment of FIG. 1, the only difference being the year date ring incorporated on the cross bars;

FIG. 7 is a fragmentary top plan view of FIG. 6;

FIG. 8 is a fragmentary bottom plan view of an alternate embodiment of FIG. 1, the only difference being the month date ring incorporated on the cross bars; and FIG. 9 is a fragmentary top plan view of FIG. 8.

FIG. 1

FIG. 2

FIG. 3

FIG. 4

FIG. 5

FIG. 7

FIG. 6

FIG. 9

FIG. 8
